MOBILE WIRING PLATFORM ASSEMBLY

Paul V. De Luca, Port Washington, N.Y., assignor to
Porta Systems Corp., Roslyn, N.Y.

Filed May 22, 1972, Ser. No. 255,966

Term of patent 14 years

Int. Cl. D12—02

U.S. Cl. D12—59

FIG. 1

FIG. 2

FIG. 5

FIG. 4

FIG. 3

FIG. 1 is a perspective view of the mobile wiring platform assembly embodying my new design;

FIG. 2 is a top plan view;

FIG. 3 is a front elevational view;

FIG. 4 is a right side elevational view; and

FIG. 5 is a rear elevational view thereof.

The surface of the steps are provided with broken lines to indicate a contrasting material.

I claim:

The ornamental design for a mobile wiring platform assembly, substantially as shown and described.
